Primary Examiner — Elizabeth J Oswecki(74) *Attorney, Agent, or Firm* — Banner & Witcoff, Ltd.(57) **CLAIM**

The ornamental design for a shoe, as shown and described.

DESCRIPTION

FIG. 1 is a front perspective photographic view of a shoe showing my new design; and,
FIG. 2 is a side photographic view thereof.

The lighter grey photographic areas are for the purpose of illustrating portions of the shoe which form no part of the claimed design.
